Primary Examiner — Brett Miller*Assistant Examiner* — Jessica M Gebhart(74) Attorney, Agent, or Firm — Wilmer Cutler Pickering Hale and Dorr LLP(57) CLAIM

The ornamental design for a tote as shown and described.

DESCRIPTION

FIG. 1 is a front view of a tote;

FIG. 2 is a back view thereof;

FIG. 3 is a left side view thereof;

FIG. 4 is a right side view thereof;

FIG. 5 is a top view thereof; and,

FIG. 6 is a bottom view thereof.

The surface treatment, color, and grayscale variation form no part of the claimed design. In FIG. 6, the broken lines form no part of the claimed design but serve as an unclaimed boundary. Furthermore, in FIG. 6, the areas within the broken lines that are in half tone portions show portions of the tote that form no part of the claimed design.
